DESIGN FOR A FAUCET CONNECTION

J Leroy Sutton, Buffalo, and Joseph Van Walshauser, Kenmore, N. Y.

Application June 21, 1934, Serial No. 52,268

Term of patent 7 years

To all whom it may concern:

Be it known that we, J LEROY SUTTON and JOSEPH VAN WALSHAUSER, citizens of the United States, residing at Buffalo and Kenmore, respectively, in the county of Erie and State of New York, have invented a new, original, and ornamental Design for Faucet Connections, of which the following is a specification, reference being had to the accompanying drawing, forming part thereof.

The figure is a perspective view of the faucet connection showing our new design.

We claim:

The ornamental design for a faucet connection
as shown.

J LEROY SUTTON.

JOSEPH VAN WALSHAUSER.
